ERNST PAUL LEHMANN, OF BRANDENBURG-ON-THE-HAUEL, GERMANY, ASSIGNOR TO THE FIRM ERNST PAUL LEHMANN, PATENTWERK, OF BRANDENBURG-ON-THE-HAUEL, GERMANY.

LOCKING MEANS FOR THE SPRING DRUMS OF CLOCKWORK MECHANISMS.

Application filed September 25, 1925, Serial No. 58,657, and in Germany November 3, 1924.

In ordinary commercial spring operated clockwork mechanisms, more particularly those of the simplest form for toys, the resistance for preventing the mechanism turning in the reverse direction, when the spring is wound up, is either provided in connection with the casing of the clockwork or directly in connection with the toy itself. The check is formed either by a separate spring-loaded detent or in many cases (for the sake of cheapness in the manufacture of articles by mass production) by the body or wall of the toy itself (for instance a toy motor car). The simplest form in the latter case is the provision of a projecting tooth punched up from the sheet metal body, behind which the opposing teeth of the ratchet wheel are caused to engage through the laterally directed opposing pressure of the spring drum and thereby to prevent the drum from running down in the opposite direction to that of winding.

This latter simplest arrangement adopted for the sake of cheapness has in many cases the drawback, that the laterally directed check to the spring provided by the casing (for instance in the case of toy motor cars open at the bottom), is not always uniform, in the case of articles made by mass production with cheap labour, or easily gets bent aside subsequently in use. This drawback is completely overcome by the present improvement, through the provision of a small intermediate disc (the cost of which is negligible) which is prevented from turning in the reverse direction by means of a projection or pin projecting at one side

through the casing, but otherwise remains laterally movable and thereby finds an abutment against the teeth of the ratchet wheel, 40 which are preferably bent over laterally.

This locking disc may of course be made of any suitable material, which will in most cases be sheet metal, but may in certain cases be celluloid or some other thin material. 45

The invention is illustrated diagrammatically in Figs. 1 to 3 of the accompanying drawing by way of example. 1 is the wall of the toy or any other fixed surface of the toy. 2 is the shaft and 3 the hole for the 50 shaft. 4 is the disc referred to with a tooth or tongue 5. In Fig. 1 the parts 1, 4, 5 and 6 are shown somewhat spaced apart. The disc 4 is secured at 7 against rotation. 6 is the wheel to be locked. 55

What I claim is:—

Locking means for the spring drums of clockwork mechanisms, comprising in combination a casing, a shaft for the spring drum, a ratchet wheel on the spring drum, a locking disc mounted on the said shaft and interposed between the wall of the casing and the ratchet wheel, a detent on the said locking disc capable of engaging with the teeth on the ratchet wheel, the disc with its detent being free to move laterally, and a member projecting through the wall of the casing for securing the locking disc against rotating in the direction of rotation of the drum, as and for the purpose set 70 forth. 60

In testimony whereof I have signed my name to this specification.

ERNST PAUL LEHMANN.
